UNITED STATES PATENT OFFICE.

EVERETT J. COOK, OF TOLEDO, OHIO, ASSIGNOR TO THE DURA COMPANY, OF TOLEDO, OHIO, A CORPORATION OF DELAWARE.

DESIGN FOR A LIGHT GLOBE.

Application filed March 19, 1923. Serial No. 5,522. Term of patent 7 years.

To all whom it may concern:

Be it known that I, EVERETT J. Cook, a citizen of the United States of America, residing at Toledo, in the county of Lucas and State of Ohio, have invented a certain new, original, and ornamental Design for Light Globes, of which the following is a specification, reference being had therein to

the accompanying drawings forming part thereof, in which Fig. 1 is a side view of a globe showing the improved design; and Fig. 2 is a bottom view of the same.

I claim:

The ornamental design for a light globe, substantially as shown.

EVERETT J. COOK.
